UNITED STATES PATENT OFFICE

WILLIAM KREIELSHEIMER, OF NEW YORK, N. Y., ASSIGNOR TO NATHAN & COHEN CO., INC., OF NEW YORK, N. Y., A CORPORATION OF NEW YORK

DESIGN FOR A MUFFLER

Application filed October 5, 1929. Serial No. 32,955. Term of patent 3½ years.

To all whom it may concern:

Be it known that I, WILLIAM KREIELSHEIMER, a citizen of the United States, residing in Queens County, city of New York, State of New York, have invented a new, original, and ornamental Design for a Muffler, of which the following is a specification, reference being had to the accompanying drawing, forming part thereof.

The figure of the drawing is a plan view of approximately a quarter section of a muffler, showing my new design.

The dot and dash lines shown in the drawing define a one-quarter section of the motif constituting the complete design. The other three sections of the design are identical and continue in proper relation to the section shown.

I claim:

The ornamental design for a muffler substantially as shown and described.

WILLIAM KREIELSHEIMER.
